UNITED STATES PATENT OFFICE.

JOHN H. LEYSON, OF BUTTE, MONTANA.

DESIGN FOR A BADGE.

SPECIFICATION forming part of Design No. 23,021, dated January 30, 1894.

Application filed November 14, 1893. Serial No. 490,961. Term of patent 3½ years.

To all whom it may concern:

Be it known that I, JOHN H. LEYSON, a citizen of the United States, residing at Butte, in the county of Silver Bow and State of Montana, have invented and produced a new and original Design for a Badge, of which the following is a specification.

Reference is to be had to the accompanying drawing, forming a part of this specification, in which the figure represents a face view of a badge embodying my new design.

The leading feature of the design consists in the ornamentation shown, consisting of the ornamental figure *a*, representing a perspec-

tive view of a steam drill in working position, 15 with the hose *b* curved and passing at the back of the drill and behind the representation of rock *c*, and the circular border composed of the concentric circular bands *e e'*.

A minor feature of the design is the representation of a drill hole, *d*. 20

I claim—

The design for a badge herein shown and described.

JOHN H. LEYSON.
